Primary Examiner — Susan E Krakower*Assistant Examiner* — Lisa A Grabenstetter(74) *Attorney, Agent, or Firm* — Avery N. Goldstein; Blue Filament Law PLLC(57) **CLAIM**

The ornamental design for a handbag, as shown and described.

DESCRIPTION

FIG. 1 is a perspective view of a handbag showing my design;

FIG. 2 is a front view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

The broken line features that appear on the bottom of the handbag represent unclaimed portions of the design.

Dashed lines associated with the edges of panels of the handbag denote stitching and constitute portions of the claimed design.
